UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A DISH.

SPECIFICATION forming part of Design No. 27,743, dated October 19, 1897.

Application filed September 8, 1897. Serial No. 650,995. Term of patent 3½ years.

To all whom it may concern:

Be it known that I, WILLIAM H. GRINDLEY, a citizen of Great Britain, residing at Congleton, Cheshire, England, have invented a certain new and original Design for a Dish; and I do hereby declare the following to be a full, clear, and exact description of the same, reference being had to the accompanying drawings, forming a part hereof.

10 In the drawings, Figure 1 is a top plan view of a dish embodying my design. Fig. 2 is a central longitudinal section, and Fig. 3 a central transverse section thereof.

The leading features of my design are as follows: The dish is oblong in shape and has a flat bottom and sloping rim. The rim is ornamented at its outer edge. The ornamentation consists of two side panels or sectors *a* and *b* and two end panels or sectors *c* and *d*. Each side panel has an external band consisting of a convex curve *x*, reversed at *y* and *z* and terminating as at *m* and *n*, where it joins the bands of the end panels to cusps *c*.

Within this band and parallel thereto are arranged a series of curved scallops *s*, which terminate in a scroll *t* at each end of the panel, and which scroll is tangent to the adjacent scroll of the adjoining panel. Each end panel is provided with a similar external band, within which is arranged a similar series of 25 curved scallops terminating in a scroll, as *r*. At the center of each end panel is a rococo-embossed ornamentation *o*, consisting of a central foliate scroll *p* and side shell-like ornaments *q* and *q'*.

30 What I claim as new is—

The design for a dish substantially as shown and described.

In testimony whereof I have signed this specification in the presence of two subscribing witnesses.

WILLIAM H. GRINDLEY.
